CLAIM

The ornamental design for an automobile organizer, as shown and described.

DESCRIPTION

FIG. 1 is a perspective view of the automobile organizer of the present invention;

FIG. 2 is a top plan view of the automobile organizer of the present invention;

FIG. 3 is a bottom plan view of the automobile organizer of the present invention. The phantom lines indicate the shape of the bottom but are not intended to be a part of the claim;

FIG. 4 is a right side elevation view thereof;

FIG. 5 is a left side elevation view thereof;

FIG. 6 is a front elevation view thereof; and,

FIG. 7 is a rear elevation view thereof.

1 Claim, 4 Drawing Sheets
